DESIGN FOR A WHEELED FIRE EXTINGUISHER

Walter H. Freygang, Essex Fells, N. J., assignor to
Specialties Development Corporation, Bloom-
field, N. J., a corporation of New Jersey

Application April 19, 1940, Serial No. 91,776

Term of patent 14 years

To all whom it may concern:

Be it known that I, Walter H. Freygang, a citizen of the United States, residing in Essex Fells, in the county of Essex, in the State of New Jersey, have invented a new, original, and ornamental Design for Wheeled Fire Extinguisher, of which the following is a specification, reference being had to the accompanying drawing, forming a part thereof.

Figure 1 is a perspective view of a wheeled fire extinguisher embodying my design, while

Figure 2 is a bottom plan view of the wheeled fire extinguisher shown in Figure 1.

The device presented in the drawing is of symmetrical construction, the side opposite to that shown in Figure 1 being substantially the same as illustrated.

I claim:

The ornamental design for a wheeled fire extinguisher, substantially as shown and described.

WALTER H. FREYGANG.
